UNITED STATES PATENT OFFICE.

ANDREWS ALLEN, OF CHICAGO, ILLINOIS, ASSIGNOR TO WOOD EQUIPMENT COMPANY, OF CHICAGO, ILLINOIS, A CORPORATION OF ILLINOIS.

CAR-TIPPLE.

1,265,028.

Specification of Letters Patent.

Patented May 7, 1918.

Application filed September 28, 1917. Serial No. 193,755.

To all whom it may concern:

Be it known that I, ANDREWS ALLEN, a citizen of the United States, residing in Chicago, in the county of Cook and State 5 of Illinois, have invented new and useful Improvements in Car-Tipples, of which the following is a specification.

This invention relates to improvements in car tipples and more especially to a certain 10 arrangement and combination of apparatus and mechanism associated with a rotary tipple for properly handling the cars through the tipple in the overturning and dumping operation of the latter. The improved apparatus 15 and devices here illustrated are designed more particularly for use in combination with a tipple of the kind known as a rotary tipple, in which the cars, singly or in trips of two or more, enter a rotating structure and are overturned sidewise to 20 discharge their contents. The cars are ordinarily brought to the tipple in trains along a connecting stretch of fixed track, which joins a pair of rails in the lower part of the 25 tipple, and after the dumping operation is completed the cars leave along a corresponding length of stationary track which meets the tipple at its opposite end; it having heretofore been found to be practical to provide the cars with swiveling couplings so 30 that the dumping operation may be carried on without uncoupling the cars in the train. The present invention relates more particularly to means for handling a train of loaded 35 cars in the approach to the tipple, moving them forward intermittently a distance corresponding to the length of one or more cars, periodically and automatically stopping the train in such manner as to "spot" one or 40 more cars in the tipple and holding the train stationary for each dumping operation, and then continuing its movement to 45 pass the unloaded cars out of the tipple and introduce one or more loaded cars for the next operation.

An apparatus embodying the principles of the invention is illustrated in the accompanying drawings in which:

Figure 1 is a view in side elevation showing 50 a portion of the receiving end of a rotary tipple of well known form, a stretch of stationary track leading to the tipple and some of the mechanism associated therewith.

Fig. 2 is a similar view showing the discharge end of the tipple, a stretch of sta-

tionary track connected therewith, and parts of the mechanism related thereto.

Fig. 3 is a top plan view of the same parts shown in Fig. 1.

Fig. 4 is a top plan view of the same parts shown in Fig. 2.

Fig. 5 is a view in side elevation showing a chain-drive mechanism for advancing the cars successively into and through the tipple.

Fig. 6 is an enlarged detailed view showing a portion of the drive-chain with one of the parts for engaging a car.

Fig. 7 is a vertical section on the line 7--7 of Fig. 6.

As shown in said drawings, 10 indicates 70 in outline merely a cylindrical tipple structure which may be of any well known type, the same being mounted on wheels, 11, and arranged to rotate about a horizontal axis. The cylinder is open at each end and is provided with rails extending through its entire 75 length to receive one or more cars, which latter enter the tipple along a stretch of stationary track, 15, pass through the tipple, and leave over a length of track 20. The cylinder 10 may be made of any practical 80 length according to the number of cars which it is intended to accommodate, and in the dumping operation the cars may be brought up in a long train and overturned 85 successively without being uncoupled. A rotary tipple or structure similar to that here shown, with stretches of fixed track approaching and leaving the tipple, has been used heretofore, and the particular design 90 and construction of these parts are no part of the present invention.

Adjacent to the section of track 15 approaching the receiving end of the tipple 10 is arranged the driving mechanism for advancing the cars into and through the tipple through a long chain, 25, which latter is arranged between the two rails. Accordingly there are journaled beneath the track bed a pair of large sprockets, 26 and 27, over 100 which is trained the chain 25; and on this chain there are fixed at the required distances car pushers for engaging the cars. One of these car pushers is illustrated in Figs. 6 and 7 and includes two pairs of flat 105 plates, 30 and 31, which take the place of the two side plates of an ordinary link, but are somewhat widened so as to project above the pitch line of the chain and provide journals for a pair of pivoted levers 35, 35. 110

Each of the levers, 35, 35, is made with an upright extending part, 36, and with a weighted horizontal extension, 37, so that when these parts are in the upper part of 5 the chain travel the levers will stand upright, as shown in Fig. 7. In these positions they are adapted to engage with spurs, 40, one of which projects downward from each car, so that as one of the car pushers approaches beneath the car and the spur 40 is 10 engaged by an inclined forward face on one of the levers 35, the latter will swing downward and permit the spur to be engaged between the two adjacent faces, 36. The two 15 plates 30 and the two plates 31 of the two driving links also form journals for transverse shafts, 42, on which are flanged wheels, 43, running on a pair of horizontal rails, 44, to guide the upper length of chain between 20 the two sprockets and take the vertical component of the thrust of the driving links against the cars so that the links will not become disengaged; and in addition the chain is provided at intervals with rollers, 48, 25 which likewise run on the rails 44 and keep the chain from dragging.

The driving chain 25 is driven through machinery located adjacent to the fixed approach track, which is best shown in Fig. 3. 30 This machinery includes a motor or other source of power, 55, which is geared to a shaft 56 through a pinion and gear, 57 and 58, respectively, the shaft 56 having fixed to it a heavy fly wheel, 60, to assist the motor in 35 taking up the load when the machinery is started as will be described hereinafter. The shaft 56 in turn is geared through reduction gearing, 61, to a shaft 63, and on this shaft is a clutch, 65, by means of which 40 it may be engaged with a shaft 66 carrying the chain sprocket 27; the clutch 65 being of well known form and its particular design or construction not constituting any part of the present invention. The clutch 45 is engaged and disengaged through a set of clutch dogs 70 and a sliding cone 71, with a collar and a long lever 75 to impart movement to the clutch collar. The end of the lever 75 is connected through a bell-crank 50 lever 76 and a rod 77 to a hand and foot lever 78, and it will be seen that a movement of the upper end of the lever 78 to the left, as it is illustrated in Figs. 1 and 3, will act to wedge the clutch cone between the ends 55 of the clutch dogs and engage the clutch; while a reverse movement of the lever will act to disengage the clutch.

In addition there is provided a brake drum 80, with a brake band 81, on the shaft, 60, 66, the brake band being contracted on the drum by the downward movement of an arm 85 carrying a weight 86; and the brake is released through a cable 88 passing over pulleys and connected to the clutch lever 75, 65 so that a movement of this lever to engage

the clutch will automatically release the brake and a reverse movement of the lever to throw out the clutch will permit the brake to be applied through the weighted arm, 85.

It will thus be seen that when the hand lever 78 is operated to set the machinery into motion, the driving chain 25 will be started to engage with the cars and draw them toward the tipple and their forward movement will continue until they are automatically stopped by other parts of the apparatus which are designed and arranged as follows:

The movement of the clutch lever 75 to engage the clutch also acts through a rod 95 and a bell-crank lever 96 to pull on a cable 97 which is connected to a crank arm 98 on a transverse shaft 99 below the track bed and under the top part of the chain 25; the shaft 99 having fixed to it an upwardly projecting crank arm 100. When the clutch 65 is engaged to start the machinery as above described the pull imparted through the rod 95 and the cable 97 to the arm 98 on the shaft 99 sets the crank 100 in an upright position, as shown in Fig. 1, and the cars are then impelled forward until the upper end of the crank arm 100 is engaged by a lug 105 on the chain; which imparts a reverse movement to the shaft 99. This is transmitted back through the cable 97 and 95 the rod 95 and pulls the clutch out of engagement and applies the brake 81 to stop the machinery. The driving chain 25 is provided with one or more lugs, 105, spaced according to the number of cars which are 100 to be accommodated in the tipple for each dumping operation so that the machinery will be stopped at the required intervals; and accordingly in the design here illustrated, which is adapted to handle two cars 105 in the tipple for each operation, the chain is shown with four car-pusher links, of which latter two alternate ones are each provided with a stopping lug, 105, formed by making the side plates 31 of one link 110 considerably wider than the others and shaping these plates to provide triangular projections below the pitch line of the chain.

In addition to the automatic stopping and braking of the driving machinery as above 115 described, means are provided for automatically spragging the cars on their rails to hold the train stationary for the dumping operation, these means comprising parts as follows:

At a point in the track bed below the fixed piece of approach track leading to the tipple there is arranged a heavy curved horn or stop 120 which is hinged at one end and adapted for upward or downward movement 125 about its pivot point to engage a wheel of one of the cars, or to release the wheel from engagement. The horn is raised and lowered through a pair of toggle links 125, which latter are operated through a crank 130

arm 126 on a toggle shaft 127. To the end of the crank arm 126 is fastened a long cable 128 which is led over a sheave and connected at its other end through a bell-crank lever 130 and a rod 131 with the clutch lever 75, so that the movement of the clutch lever to engage the clutch, as above described, will act through the bell-crank lever 130 to impart a pull on the cable 128 and to the toggle 10 arm 126. This bends the toggle joint and draws the horn 120 downward, thus releasing the cars and permitting them to travel forward. When the toggle joint is thus bent to withdraw the horn it is latched in its 15 bent position by a hooked lever 140 which engages a pin 141 in the toggle joint, so that the horn is held down, against the action of a counter weight 142 which tends to raise the horn. The latch 140 is connected 20 through a bell-crank lever 145 and a rod or cable 146 with a crank arm 148 on the shaft 99, so that the action of these parts is as follows:

When the clutch is engaged to set the 25 driving machinery into motion the pull on the cable 128 bends the toggle joint to withdraw the car stop 120, which latter is then latched in its released position by the latch lever 140. When the cars have run the required 30 distance and one of the lugs 105 engages the end of the crank arm 100 to rotate the shaft 99 and withdraw the clutch and apply the brakes as above described, the same movement of the shaft 99 acts through 35 the rod 146 and raises the latch lever 140, thus permitting the counter weight 142 to set the horn and hold the car.

In the track bed of the fixed piece of track beyond the tipple there is arranged a car 40 stopping and holding mechanism in all respects similar to the horn 120 and its related parts, the second car stopping mechanism comprising a horn or stop 160 similarly actuated through a counter weight 161 45 to raise it into its operative position, and released through a pair of toggle links 164; with a latch lever 165 to hold it in its released position. The toggle links are bent to withdraw the horn through a crank arm 50 170 and a long cable 171, which latter is led over a sheave and connected to a third arm, 172, of the bell-crank lever 130; so that the same movement of the latter which releases the horn 120 likewise releases the horn 160. 55 Similarly the latch lever 165 is withdrawn, to release the toggle latch and permit the horn to be set, by a long cable 180 which is connected with a crank arm 181 on the shaft 99 carrying the arm 98; so that the same 60 movement of this shaft which withdraws the latch 140 will likewise withdraw the latch 165 and permit the two horns to be set together, and the train will be spragged on each side of the tipple during the dumping 65 operation. The purpose of such double

spragging is to hold the train with the couplings slack and the bumpers apart, thus permitting the car or cars in the tipple to overturn freely.

In the operation of the complete mechanism the motor 55 is first started and the driving machinery set into motion through the lever 78 and the clutch arm 75, to start the driving chain and move the cars forward; this same operation of the parts setting the lever 100 into an upright position and in the path of movement of the two lugs 105. The train of cars will then be driven forward until one of the lugs 105 engages the upper end of the crank-arm 100, 75 which will impart a pull back through the cable 97 and the rod 95 to withdraw the clutch and apply the brake; and the same movement of the parts will withdraw the two latch levers 140 and 165 and permit the 80 two horns or stops to come up and hold the train stationary while the tipple is operated. As soon as the cars in the tipple have been restored to their upright position the lever 78 may be operated to release the two car 85 stops and again set the machinery into motion and continue the forward movement of the train.

I claim as my invention:

1. The combination with a rotary tipple 90 having rails adapted to receive a car and a stationary track connecting with the rails in the tipple, of means for propelling a train of cars along the stationary track, and means for automatically stopping the train 100 after a pre-determined distance of travel.

2. The combination with a rotary tipple 105 having rails adapted to receive a car and a stationary track connecting with the rails in the tipple, of means for propelling a train of cars along the stationary track, and means for automatically stopping and holding the train after a pre-determined distance of travel.

3. The combination with a rotary tipple 110 having rails adapted to receive a car and a stationary track connecting with the rails in the tipple, of a driving mechanism for propelling a train of cars along the stationary track, and means actuated by such mechanism for automatically stopping the same.

4. The combination with a rotary tipple 120 having rails adapted to receive a car and a stationary track connecting with the rails in the tipple, of a driving mechanism for propelling a train of cars along the stationary track, and means actuated by such mechanism for automatically stopping and holding the train stationary.

5. The combination with a rotary tipple 125 having rails adapted to receive a car and a stationary track connecting with the rails in the tipple, of means for propelling a continuous train of cars along the stationary track and through the tipple, and means for 130

4

holding the train stationary at points on each side of the tipple to permit the overturning of a car in the train.

6. The combination with a rotary tipple 5 having rails adapted to receive a car and a stationary track connecting with the rails in the tipple, of a horizontally moving part adapted to engage with a car in a train to propel one of the cars into the tipple, and 10 means acting automatically in the movement of such part to stop the train.

7. The combination with a rotary tipple 15 having rails adapted to receive a car and a stationary track connecting with the rails in the tipple, of a driving chain having a part adapted to engage a car in a train to propel the train along the stationary track, means for driving the chain, and means actuated by a part on the chain to disconnect 20 the driving means and stop the train.

8. The combination with a rotary tipple 25 having rails adapted to receive a car and a stationary track connecting with the rails in the tipple, of a driving chain having a part adapted to engage a car in the train and to propel the train along the stationary track, driving machinery for imparting movement to the chain, means for connecting the driving machinery to the chain and for 30 disconnecting it therefrom, a moving part on the chain, another part adapted for engagement by the moving part on the chain, and means acting through the engagement of such two parts to disconnect the driving 35 machinery from the driving chain.

9. The combination with a rotary tipple having rails adapted to receive a car and a stationary track connecting with the rail. 40 the tipple, of a car stop in the stationary track, a driving chain having a part adapted to engage a car in a train to propel the train along the stationary track, a moving part on the chain and a part on the fixed track adapted for engagement by the moving part on the chain, and means acting through the engagement of such two parts to set the stop and arrest the motion of the train. 45

10. The combination with a rotary tipple having rails adapted to receive a car and a stationary track connecting with the rail. 50 in the tipple, of means for propelling a train of cars along the stationary track and through the tipple, and means acting automatically after a pre-determined distance of the train's travel to stop the train and to hold it at a point on the stationary track. 55

11. The combination with a rotary tipple having rails adapted to receive a car and a stationary track connecting with the rail. 60 in the tipple, of means for propelling a train of cars along the stationary track and through the tipple, and means acting automatically after a pre-determined distance of the train's travel to stop the train and to hold it at a point on the stationary track on each side of the tipple. 65

In witness whereof, I have hereunto subscribed my name this 25th day of September, 1917.

ANDREWS ALLEN.
